GLOVE

Rosa B. Wilson, Akron, Ohio, assignor to The
B. F. Goodrich Company, New York, N. Y., a
corporation of New York

Application September 13, 1949, Serial No. 4,979

Term of patent 14 years

(Cl. D3—11)

To all whom it may concern:

Be it known that I, Rosa B. Wilson, a citizen of the United States of America, residing at Akron, in the county of Summit and State of Ohio, have invented a new, original, and ornamental Design for a Glove, of which the following is a specification, reference being had to the accompanying drawing, forming a part thereof.

In the drawing:

Fig. 1 is a front elevational view of a glove, showing my new design as it appears with the thumb bent back.

Fig. 2 is a rear elevational view, and

Fig. 3 is a sectional view thereof taken along line 3—3 of Fig. 1.

I claim:

The ornamental design for a glove, as shown.

ROSA B. WILSON,
